(57) **CLAIM**

The ornamental design for a wearable drug delivery device
baseplate, as shown and described.

DESCRIPTION

FIG. 1 is a top perspective view of a wearable drug delivery device baseplate in accordance with an embodiment of the present invention;

FIG. 2 is a bottom perspective view of the drug delivery device baseplate;

FIG. 3 is a top plan view of the drug delivery device baseplate;

FIG. 4 is a left side elevational view of the drug delivery device baseplate;

FIG. 5 is a right side elevational view of the drug delivery device baseplate;

FIG. 6 is a front elevational view of the drug delivery device baseplate;

FIG. 7 is a back elevational view of the drug delivery device baseplate; and,

FIG. 8 is a bottom plan view of the drug delivery device baseplate.

1 Claim, 6 Drawing Sheets
